UNITED STATES PATENT OFFICE.

PAUL J. RAY, OF LAKewood, OHIO.

ADJUSTABLE FIELD-RHEOSTAT.

1,070,629.

Specification of Letters Patent. Patented Aug. 19, 1913.

Application filed September 3, 1912. Serial No. 718,428.

To all whom it may concern:

Be it known that I, PAUL J. RAY, a citizen of the United States, residing at Lakewood, in the county of Cuyahoga and State of Ohio, have invented a new and useful Adjustable Field-Rheostat, of which the following is a specification.

The present invention relates to improvements in adjustable field rheostats.

The particular rheostat hereinafter set forth is designed to be used in connection with a direct current motor so that the speed of the direct current motor can be varied or adjusted by inserting the resistance in series with the shunt field, this particular structure being designed to give infinitesimal speed changes, whereby the motor may have imparted thereto maximum speed.

In view of the fact that the torque of a direct current motor decreases as its speed is increased by the insertion of resistance in the shunt field, and as it is generally preferable to start a direct current field controlled motor at low speed, which speed gives maximum torque, it is desirable to use a field rheostat which automatically cuts out all resistance in series with the shunt field, when the line voltage is interrupted whether because of disconnecting the motor from the line or other disturbances.

The primary object therefore of the present invention is the provision of an adjustable field rheostat, which will attain the foregoing features and will permit of the actuation of the motor at any variance of speed from the minimum to the maximum.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a top plan view of the complete rheostat, with the dome or casing shown in section, an electrical diagram being connected to the rheostat to show the insertion thereof in series with the shunt field of a motor. Fig. 2 is a side elevation of the mechanism, a section being taken through the longitudinal central line of the cover, and the operating lever being shown at its lowermost position. Fig. 3 is

a similar view to Fig. 2 with the automatic means for releasing the lever. Fig. 4 is a diagrammatic view of the full electrical connection used with the form of rheostat as shown in Fig. 3. Fig. 5 is a plan view of a portion of the cover showing the scale and lever index to indicate the speed of the motor controlled by the rheostat.

As the main features of the present rheostat are used in connection with the manually operated lever and also the automatically operated lever, the description of the same will be referred generally as applying to all views.

Referring to the drawings, the numeral 1 designates the base of the rheostat carrying the cover 2, which is provided with the elongated slot 2', said slot being positioned for the protrusion of the handle of the lever 3, the detailed construction and assemblage of which will be described later on.

Fixedly carried by the base 1, either integrally or otherwise, is a plate 4 which has secured thereto upon the inner face the two bushings or disks 5 made of insulation, such insulation either being hard paper fiber or mica as may be desired, and although only two of the said disks are shown, it is evident that one or in fact any number may be used according to the desired amount of resistance needed, as will presently appear. Connected to the upper ends of the respective plates 4 by screws 7, and above each bushing 5, are the plates 6 also made of insulation the same extending in parallel and being connected by the slots 8 and screws 9 to the upper end of the adjustable plate 10, said plate 10 being constructed similarly to the plate 4 and at the opposite end of the base 1. The foot or base 11 of the plate 10 is provided with the two slots 12, through which project the bolts or screws 13, thus providing a means for adjustably connecting the plate 10 to the base 1. This construction permits of the easy assemblage of the parts of the rheostat as will presently appear.

Mounted in the respective plates 4 and 10 are the two cylindrical bolts or tie rods 14, the heads 14' of which abut the plate 4, while the lock nuts 14^a disposed upon the opposite ends thereof abut the outer face of the plate 10. The particular office of the respective bolts or tie rods will be set forth later on.

Connected adjustably to and carried by the plate 10 are the two cylindrical guide

pins 15, which are secured to said plate 10 by means of the respective nuts 16-16' so that their relative position is maintained at all times. Slidably mounted upon both 5 of the pins 15 is a transversely disposed plate or bar 17 which also is slidably mounted upon the respective bolts or tie rods 14, and upon the face of the said bar 17 opposed to the face of the plate 4 are the two 10 disks or bushings 18 of insulation. Disposed upon the respective tie rods or bolts 14 between the plates 4 and bar 17 is a bushing or sleeve 19 of insulation, which with the disks 5 and 18 insulates the conductors 15 disks 20 disposed upon the tube 19 of insulation and between the respective pairs of disks 5 and 18. These disks 20 are preferably made of graphite or carbon, and are disposed to be compressed and released 20 to decrease and increase the resistance placed in the shunt with the field of the motor. As shown, two columns of these disks 20 are provided and as the surfaces thereof when made of graphite or carbon, are comparatively rough, it is evident that when the compression is gradually released, the surface contact between the disks is therefore gradually broken to adjustably increase the 25 resistance of such columns of disks and in 30 turn to increase the resistance inserted in series with the shunt field of the motor. The compression of said disks will decrease the resistance so that the minimum speed required in the motor can be attained. Under 35 normal conditions, the disks 20 are held compressed by the two springs 21, there being one spring to each column of disks, said springs being disposed upon the respective bolts or tie rods 14 between the plate 10 and 40 bar 17, the force of the said springs being exerted away from the plate 10 and upon such bar 17.

In order to provide a means for adjustably increasing the resistance, that is reducing the compression upon the respective 45 columns of disks, the bar 17 upon the face abutting the respective disks 18 of insulation, is provided with the two apertured lugs 22 in which is mounted the pin 23, said pin 50 23 having disposed thereon between the lugs 22, an anti-frictional roller 24, said roller being disposed in the path to be engaged by the lower cam end 3' of the operating lever 3.

55 In order to properly mount the lever 3, two apertured lugs 25 carrying the lever pivoting pin 26 are themselves carried by the plate 27. In the under side of the base plate 1 are provided recesses and elongated slots 60 28, through which project the screws 29 for locking the plate 27 in adjusted position. In order to provide means for adjusting the plate 27 when the screws 29 have been released, and thus regulate the position of the 65 cam end 3' of the lever 3 relatively to the

anti-frictional roller 24, a screw threaded lug 30 is provided upon the inner end of the plate 27, and is engaged by the feed screw 31 which is mounted in and at the base of the plate 10, the head 32 thereof being disposed to be readily accessible for imparting the necessary movement to the plate 27. 70

Where the handle 3 is used to be held at any point, to maintain the same in position, a flat spring 33 is carried thereby, as clearly 75 shown in Fig. 2 and is disposed to engage the adjacent face of the slot 2' of the cover 2 and offers sufficient resistance to maintain the lever in any adjusted position in the slot 2'. 80

In the form of rheostat shown in Fig. 3, the electromagnet 35 is mounted between the respective disks 36 and 37 upon the handle or lever 3 within the dome or cover 2, the same being so constructed and electrically 85 connected, as will presently appear, to exert a magnetic pull upon the cover adjacent the slot 2' sufficient to overcome the tension of the spring 34, whose normal tension is to hold the lever in the position as shown in 90 Fig. 3, thus providing a means whereby the lever 3 may be left in any position within the slot 2' as long as the line voltage to the motor 50 is not disturbed to any great extent. Should the line voltage be disturbed, 95 the coil 35 will be deenergized and thus release the lever 3 to the action of the spring 34 which will assume the low speed position as shown in Fig. 3.

Where the rheostat is used without the 100 electromagnet 35, the circuit is as follows: The current is led to the motor 50 through the mains M-M', a conductor 51 being disposed relatively to the motor 50 so as to form a shunt with the field thereof, said conductor 51 being led to a post 52 carried by and insulated from the base 1 of the rheostat, the conductor 53 being connected to the first column of conducting disks 20, said columns being connected at the opposite 110 ends through the medium of the conductor 100, the conductor 54 being connected to the other column of disks 20 and through the post 55, connected to and insulated from the base 1 of the rheostat, while the conductor 115 56 is led from the post 55 to the shunt field 57 of motor which is connected by means of the conductor 58 to the opposite common line and motor armature terminal of the 120 motor 50.

It will thus be seen that when the elements are in the position as shown in Fig. 1, that the rheostat will be in its lowest resistance position and that the maximum current will be flowing through the shunt field of the 125 motor 50, but should it be desired to decrease the speed of the motor by increasing the resistance, the lever 3 is moved upwardly so that the cam end 3' thereof will abut the anti-frictional roller 24, thus moving the bar 130

17 against the tension of the springs 21 and permitting the separation of the respective columns of disks 20, whose surfaces as before described being comparatively rough, 5 and also said disks being slightly separated will increase the resistance of the respective columns of disks, thus in turn increasing the resistance inserted in series with the shunt field of the motor. In this form, the spring 10 33 will maintain the lever 3 in any desired position relatively to the slot 2'. It will thus be seen that by lowering or raising the lever 3, any speed may be obtained within the speed range of the motor.

15 As shown in Fig. 3, and in the diagram of Fig. 4, what is termed as a "no voltage" release attachment for bringing the lever 3 to the low speed position, when the voltage is interrupted, is provided, and in this case, the 20 electromagnet 35 is connected across the main line terminals M—M' and the circuit is as follows: the main line terminal M', the conductor 51, the post 52, the conductor 32, the binding post 39 mounted upon the near bar 6, the conductor 40, the conductor 41, the binding post 42 carried by the other bar 6, the conductor 43, the binding post 44 connected to and insulated from the base 1, the conductor 45, and the main M. It will thus 25 be seen that when the current is flowing through the electromagnet 35, and under a slight variance, that the lever 3 will be maintained by the magnetic action of the electromagnet 35 upon the cover 2 adjacent to the slot 2' and at any desired adjustment within the radius of such curve of the slot 2', but that should the line voltage be disturbed, the coil 35 will be deenergized and thus release the lever to the action of the spring 34 so 30 that the lever 3 will be moved to the position as shown in Fig. 3, releasing the bar 17 to the action of the springs 21, which thus compress the disks 20 and decrease the resistance thereof. Thus it will be seen that when the lever 3 with the electromagnet 35 carried thereby is positioned at a place within the slot 2', the same will maintain such position as long as the line voltage to the motor is not disturbed to any great extent, whereas 35 in the form shown in Fig. 1, where the spring plate 33 is provided, and no spring 34 is employed, the lever 3 will of necessity be maintained at any desired adjusted position relatively to the slot 2', thus maintaining the spacing of the disks 20 in the respective columns in a fixed adjusted position. The lever 3 is provided with the index or pointer P, which points toward the gage or scale G, to indicate the various motor speeds, so that 40 the operator may set the lever 3 at any desired speed.

45 The resistance coil R, by means of the conductor r—r, is shunted across the terminals 52 and 55, and as this coil R, is of a higher resistance than the maximum resistance of

the columns of disks 20, when the lever 3 is in its uppermost position, it is apparent that it will serve to hold the field on the motor in case the resistance disks 20 should part.

From the foregoing description it is evident that with an adjustable field rheostat, constructed according to and embodying the present invention, the resistance disposed in series with the shunt field of the motor will permit of the starting of the motor at a low speed, the lever 3 at such time being moved the full length of the slot 2' if necessary, and that when the motor has attained full speed, the lever will be adjusted to maintain the same.

It will also be evident from the foregoing, that the rheostat which is constructed according to the present invention, may have its columns of disk 20 increased or decreased in number according to the necessary amount of resistance and the length of the respective columns will also be increased or decreased without departing from the spirit of the present invention.

What is claimed is:

1. An adjustable field rheostat, having a base, a pair of spaced supports carried by the base, two parallelly disposed rods connected to said supports, two series of conductor disks mounted one series upon each rod, both series combining to form a resistance medium, a plate slidably mounted upon both rods between one of the supports and the adjacent ends of the respective series of disks, two springs, one mounted upon each rod between the support and said plate for normally maintaining the series of disks compressed, a lever pivotally mounted upon the base between the rods, coacting means carried by the lever and the sliding plate for compressing the springs to increase the resistance of the series of disks, and means for maintaining the lever in adjusted position.

2. An adjustable field rheostat, having a base, a pair of spaced supports carried by the base, two parallelly disposed rods connected to said supports, two series of conductor disks mounted one series upon each rod, both series combining to form a resistance medium, a plate slidably mounted upon both rods between one of the supports and the adjacent ends of the respective series of disks, two springs, one mounted upon each rod between the support and said plate for normally maintaining the series of disks compressed, a lever pivotally mounted upon the base between the rods, a pair of lugs carried by the plate adjacent the lever, anti-frictional means carried by said lugs and disposed in the path to be engaged by the lever to move the sliding plate to compress the springs, and means for maintaining the lever in said spring compressing position.

3. An adjustable field rheostat, having a base, a cover for the base having a handle receiving slot therethrough, a pair of spaced supports carried by the base, two parallelly disposed rods connected to said supports, two series of conductor disks mounted one series upon each rod, both series combining to form a resistance medium, a plate slidably mounted upon both rods between one of the supports and the adjacent ends of the respective series of disks, two springs, one mounted upon each rod between the supports and said plate for normally maintaining the series of disks compressed, a lever pivoted upon the base and projecting
- through the slot of the cover, coacting means carried by the lever and sliding plate for compressing the springs to increase the resistance of the disks, and a spring plate carried by the lever for engagement with the adjacent portion of the cover to maintain the lever in adjusted position.
- In testimony that I claim the foregoing as my own, I have hereto affixed my signature in the presence of witnesses.

Correction in Letters Patent No. 1,070,629.

It is hereby certified that in Letters Patent No. 1,070,629, granted August 19, 1913, upon the application of Paul J. Ray, of Lakewood, Ohio, for an improvement in "Adjustable Field-Rheostats," an error appears in the printed specification requiring correction as follows: Page 2, line 126, for the word "decrease" read *increase*; and that the proper corrections have been made in the files and records of this office and are hereby made in said Letters Patent.

Signed and sealed this 24th day of February, A. D., 1914.

[SEAL.]

J. T. NEWTON,
Acting Commissioner of Patents.
